UNITED STATES PATENT OFFICE.

GEORGE M. HOLBROOK, OF CHICAGO, ILLINOIS, ASSIGNOR TO ARMOUR AND COMPANY,
OF CHICAGO, ILLINOIS, A CORPORATION OF ILLINOIS.

METHOD OF REFINING OIL.

1,169,154.

Specification of Letters Patent.

Patented Jan. 25, 1916.

No Drawing.

Application filed November 15, 1915. Serial No. 61,502.

To all whom it may concern:

Be it known that I, GEORGE M. HOLBROOK, a citizen of the United States, residing at Chicago, in the county of Cook and State 5 of Illinois, have invented certain new and useful Improvements in Methods of Refining Oil, of which the following is a specification.

My invention pertains to methods of refining or purifying oil, such for example, as 10 crude cotton-seed oil, and one of the salient features of the invention resides in the provision of a process of this kind which will produce a clarified oil of desired color with 15 a minimum loss or shrinkage in performing the process.

To effect this result it is desirable to use 20 a silicate, such as sodium or potassium silicate, to bring about a condensing or compacting of the soap-stock or foots produced, but this chemical is so employed that it will not have an injurious effect on the decolorizing or clarifying of the oil.

It has been suggested, as for example in 25 United States Patent No. 1,007,642, granted October 31, 1911, that the acidity of the crude cotton-seed oil may be first approximately overcome or neutralized by an alkaline silicate, such for example, as by means 30 of an aqueous solution of a water-soluble alkaline silicate, more specifically and preferably sodium tetrasilicate, and then the oil may be subjected to the action of sodium hydroxid effecting a precipitation of the 35 soap-stock from which the refined oil is separated.

Experience has indicated that a process of 40 this kind is objectionable because the initial use of the silicate appears to so set or fix the coloring matter in the oil that it is difficult or impossible by subsequent treatment to produce the proper clarifying effect at least without the employment of an excessive amount of sodium hydroxid and a consequent increase in the shrinkage or refining 45 loss, the latter depending largely upon the amount of sodium hydroxid used.

I have found that in order to produce the best results both as to color and shrinkage 50 or refining loss, the proposed use of such silicate for the purpose of neutralizing the fatty acids must be avoided, and, accordingly, I have invented a new and different process by which the desired end may be 55 secured.

In carrying out this novel process to produce a bleachable oil, I refine the crude cotton-seed oil by means of a mixture of aqueous solutions of caustic-alkali, either soda or potash, and an alkaline silicate, 60 either sodium, potassium, or any other basic element. In this way, the entire refining process is completed by the application of a single solution or mixture of solutions which may be prepared in advance, but the proportions of the ingredients are so chosen that the sodium silicate is in such a comparatively minor amount and in the presence of such an overwhelming quantity of hydroxid, that the deleterious effect of the 70 silicate on the coloring matter is prevented; or, stated in other words, the free fatty acids are completely neutralized or so nearly overcome by the sodium hydroxid before the sodium silicate has an opportunity to act 75 that the injurious effect upon the color referred to does not take place.

In performing this process, the percentages of ingredients or temperatures employed, etc., will be varied to conform to 80 the characteristics of the crude cotton-seed oil treated, and will depend to some extent upon the color required and the permissible loss in shrinkage. As a typical case, however, I might mention that with crude cotton-seed oil containing free fatty acids of 85 1%, there would be added to the oil a mixture composed of four per cent. (4%) by weight of the oil treated of an aqueous solution of sodium hydroxid, 18 Baumé, or 90 its equivalent in caustic strength, and three fourths ($\frac{3}{4}$) of one per cent. (1%) by weight of the oil of an aqueous solution of sodium silicate of commercial grade, i. e. 44 Baumé, the mixture being agitated for approximately 95 15 minutes and its temperature gradually raised from about 80° Fahrenheit to about 115° Fahrenheit, at which point the soap-stock will readily and completely separate from the refined oil, the latter being much clearer and of lighter color than in the crude state.

As will be readily appreciated, the sodium hydroxid is the much more active of the two chemical agents and it is enabled to so completely or nearly neutralize or overcome the free fatty acids before the silicate acts, that the setting or fixing capability of the latter on the coloring matter is avoided.

Although this process or method has been 110

described in connection with the refining and purifying of cotton-seed oil, it is to be understood that its use is not limited and restricted to any particular kind of oil, but 5 is adapted for employment in connection with many vegetable and animal oils.

I claim:

1. The process of refining crude cotton-seed oil and the like, consisting in subjecting the oil to a mixture of an aqueous solution of caustic alkali and an aqueous solution of a silicate in such proportions that the caustic alkali neutralizes either wholly or in part the free fatty acids of the oil 10 before the silicate can set or fix the coloring matter of the oil, and separating the refined oil from the soap-stock produced, substantially as described.

2. The process of refining crude cotton-seed oil and the like, consisting in subjecting the crude oil to a mixture of an aqueous solution of sodium hydroxid and an aqueous solution of sodium silicate in such proportions that the hydroxid neutralizes the free 25 fatty acids either wholly or in part before the silicate can have a setting or fixing effect on the coloring matter, and separating the refined oil from the soap-stock produced, substantially as described.

3. The process of refining crude cotton-seed oil and the like, consisting in adding to the crude oil a mixture of an aqueous solution of caustic alkali and an aqueous solution of a silicate in such proportions that the caustic alkali neutralizes the free 35 fatty acids of the oil either wholly or in part before the silicate sets or fixes the color, agitating the mixture and gradually raising its temperature, and separating the refined oil from the soap-stock produced, 40 substantially as described.

4. The process of refining crude cotton-seed oil and the like containing approximately one (1%) per cent. of free fatty acids, consisting in adding to the oil to be 45 treated a mixture composed of approximately four (4%) per cent. by weight of the oil under treatment of an aqueous solution of sodium hydroxid, 18 Baumé and approximately three-fourths ($\frac{3}{4}$) of one (1%) per 50 cent. by weight of the oil to be treated of an aqueous solution of sodium silicate, 44 Baumé, agitating the mixture and gradually raising its temperature until the soap-stock settles, and then separating the refined oil 55 from the soap-stock produced, substantially as described.

GEORGE M. HOLBROOK.
